UNITED STATES PATENT OFFICE.

ROBERT E. WENZEL AND WILLIAM M. SHOULER, OF LOS ANGELES, CALIFORNIA.

BEER-PACKAGE.

1,052,704.

Specification of Letters Patent. Patented Feb. 11, 1913.

Application filed December 20, 1909. Serial No. 534,213.

To all whom it may concern:

Be it known that we, ROBERT E. WENZEL and WILLIAM M. SHOULER, citizens of the United States, residing at Los Angeles, in the county of Los Angeles and State of California, have invented a new and useful Beer-Package, of which the following is a specification.

One object of our invention is to provide a package into which draft beer can be drawn from the original cask and from which such beer can be again drawn in quantities desired without allowing the beer within the package to part with the carbonic acid gas contained therein, thereby keeping the beer fresh and in the same condition as when drawn from the original keg or cask.

Another object of our invention is to provide a suitable package and detachable cover therefor, such cover having a siphon head, and an air inlet valve and to provide in conjunction with such cover suitable projections adapted to form hand holds to enable the cover to be screwed off from or on to the beer package.

Another object of our invention is to provide a beer package which when serving all the purposes above stated will be provided with a convenient handle which can be folded out of the way when the package is not being carried.

Our invention particularly relates to a package adapted to be used in retail trade to receive draft beer, or beer drawn from the original wood package.

The accompanying drawings illustrate our invention.

Figure 1 is a vertical section of the beer package together with the cover and siphon head. Fig. 2 is a perspective view of the spider.

1 indicates a suitable package which may be made of glass or any suitable material.

45 2 is a neck rising from the body of the package.

3 indicates screw threads cast or molded on to the neck.

4 is a cover provided with a screw threaded flange 4'.

5 is a siphon head and 6 is a siphon therefor.

7 is a spout for the siphon.

8 is a lever mounted in the siphon head 55 and adapted to operate the piston 9 to compress the spring 10 and release the valve 11

from the valve seat 12 when it is desired to draw beer from the package.

13 is a boss head carried on the upper end of the siphon 6 and is seated upon a flange 60 14 of the thimble 15.

16 indicates a swaged or spun edge of the thimble which engages with the under side of the cover 4.

17 is a screw threaded collar mounted on 65 the thimble and above the cover and is engaged and held upon such thimble between the cover and the flange 14.

18 indicates an air valve of the ordinary construction which is adapted to admit of 70 air being pumped therethrough into the interior of the package and to prevent the escape of the air therefrom.

19 is a spider carried upon the top of the cover 4 which is provided with outwardly 75 extending bail ears 20.

21 is a bail engaging with the bail ears 20 to afford convenient means for carrying the package. The bail 21 consists of two members 21', 21'', each member being provided at one end with a hook to engage with the bail ears 20 and at their other ends with hooks 23 to engage with each other.

24 indicates projecting bail rests extending outwardly from the spider and adapted 85 to engage and allow the bail members to rest therein when the bail members are disengaged from each other.

25 is a washer seated between the cover and the top of the package. 90

26 is a cap for the siphon head.

27 is a cap for the air valve.

28 indicates beer within the package and 95 29 indicates air under pressure.

30 indicates a perforation in the spider through which the air valve enters the cover.

31 is a perforation through the spider for the thimble.

The package 1 may be of any suitable shape and may be made of any suitable material and is provided with an opening and with means to engage and hold a cover to close such opening. In the form shown in the drawings we have shown the package provided with a neck having external screw threads and a cover having a screw threaded flange to screw thereupon and a washer between the flange of the cover and the base of the neck to form a hermetically sealed joint. Such cap is perforated to allow a 110 siphon to be inserted through the cover and suitable means are provided to support the

siphon in place and to mount a suitable siphon head thereupon. Such supporting means for the siphon and the siphon head comprise a thimble having a flange at its 5 upper end and having its lower end swaged or spun to flare the same outwardly to overturn its end to engage with the underside of the cover and form a tight joint therebetween. A collar having external screw 10 threads is arranged to encircle the thimble and to be seated between the flange at the upper end of the thimble and the top of the cover. A suitable siphon head having a spout for delivering beer therefrom, having 15 the customary valve and lever, is provided with internal screw threads in its body and is screwed upon the screw threaded collar. The boss head of the siphon is seated upon the top of the thimble, between 20 such thimble and the siphon head and when the siphon head is screwed down upon the collar the boss head of the siphon is clamped between the head and the thimble, thereby holding the siphon centrally. 25 To provide means whereby the package may be conveniently carried we provide suitable bail ears on the cover and a suitable bail in engagement with the ears. Such bail ears, as shown, extend outwardly beyond the edge of the cover and engage with hooks at the ends of a suitable bail. 30 In order to provide a bail which will afford a convenient means for carrying the package and provide sufficient clearance 35 above the siphon head and the lever thereof, and which can be folded out of the way when the package is not being carried, we employ a bail consisting of two members, each member having a hook at one end to 40 engage with a bail ear on the cover, and a hook at the other end to engage with the hook upon the other member. In order that such bail members may not fall down about the package or interfere with the operation 45 of the siphon head when delivering beer from the package, the two members are unhooked from each other and laid in the bail rests 24 which support them and prevent interference with the handling of the 50 package.

To provide a cover with the bail ears and bail rest, such as required, in a cheap and effectual manner, we have provided the spider 19 which is cut and formed with the 55 bail ears and bail rests from one piece of metal, and which is perforated to allow the siphon and air valve to enter the cover as shown in Fig. 2. When the cover is assembled the spider is placed on top thereof 60 and the thimble with the screw threaded collar surrounding the same is inserted through the spider and cover and the end of the thimble is then spun or upset over the cover. The siphon is then inserted 65 through the thimble with the boss head of

the siphon resting upon the upper end of the thimble. The siphon head is then screwed down upon the collar and clamps the boss head of the siphon in place upon the top of the thimble. The air valve is then inserted into the perforation in the spider and cover and fastened in any suitable manner.

When it is desired to use the package the top is unscrewed from the neck of the package and the same is filled with beer drawn from a cask, and the cover is again screwed down upon the neck to bind the cover against the washer 25. In order to screw the cover tightly against the washer it is necessary to employ considerable force and the operator may more effectually grasp the cover by placing his thumb against either one of the bail rests or ears and hooking his fingers over one of the other projecting parts, thereby enabling him to secure a perfect hold and leverage upon the cover. When the cover is screwed firmly against the washer the cap 27 of the air valve is removed and an ordinary air pump is screwed to the valve after which air is pumped into the package to create a pressure upon the beer sufficient to cause the beer to flow out through the siphon and siphon spout when the lever is operated to release the valve from the valve seat. The air under compression on top of the beer prevents the carbonic acid gas from escaping from the beer and our package will keep draft beer in perfect condition for an indefinite period without parting with the carbonic acid gas, and thereby growing stale or flat.

In practice the package may be used in retailing beer from the original wooden packages from the brewery or retail place, and the customer may draw from the package any amount of the beer desired without the remaining beer being exposed to permit the loss of the carbonic acid gas.

What we claim is:—

1. In a beer package having a neck, a cover, a spider carried on the cover, a siphon head mounted on the cover and spider, such mounting means for the siphon head consisting of a thimble, a screw threaded collar mounted on the thimble, and above the spider, the lower end of the thimble being spun to engage with the cover to bind the cover and spider between the spun end of the thimble and the collar; a siphon having a boss head, such boss head resting upon the upper end of the thimble and the siphon head screwed upon the collar to engage the siphon boss head between the upper end of the thimble and the siphon head.

2. In a cover for a beer package, such cover, an inlet valve through such cover, a thimble carried by such cover and having its end upset to engage with the cover on one side, a collar on the thimble and adapt-

ed to engage the cover on the other side, a flange on the thimble adapted to engage with the upper end of collar and hold such collar in engagement with the cover, a siphon tube having a boss head at one end, such boss head seated upon the upper end of the thimble and a siphon head in engagement with the collar on the thimble.

In testimony whereof, we have hereunto set our hands at Los Angeles, California, 10 this 13th day of December 1909.

ROBERT E. WENZEL.

WILLIAM M. SHOULER.
